George W. Walker, Pleasant Ridge, Mich., assignor to Bohn Aluminum & Brass Corporation, Detroit, Mich., a corporation

Application November 29, 1943, Serial No. 111,805

Term of patent 3½ years

(Cl. D14—3)

To all whom it may concern:

Be it known that George W. Walker, a citizen of the United States of America, residing at Pleasant Ridge, in the county of Oakland and State of Michigan, has invented a certain new, original, and ornamental Design for Station Wagon, of which the following is a specification, reference being had to the accompanying drawing forming a part thereof, wherein:

Fig. 1 is a front perspective view of a station wagon embodying my design;

Fig. 2 is a rear elevational view thereof; and
Fig. 3 is a top plan view thereof on a reduced scale.

I claim:

The ornamental design for a station wagon, substantially as shown.

GEORGE W. WALKER.
